(57) CLAIM

The ornamental design for a "chair," as shown and described.

DESCRIPTION

FIG. 1 is a perspective view of chair back showing my new design;

FIG. 2 is a front elevational view thereof;

FIG. 3 is a back elevational view thereof;

FIG. 4 is a left side elevational view thereof;

FIG. 5 is a right side elevational view thereof;

FIG. 6 is a top view thereof; and,

FIG. 7 is a bottom view thereof.

The broken line showing the remainder of the chair is for the purpose of illustrating environmental structure and forms no part of the claimed design.
